UNITED STATES PATENT OFFICE.

LUCIFER J. MOST, OF NEW YORK, N. Y., ASSIGNOR TO PENCIL PRODUCTS COMPANY, OF NEW YORK, N. Y.

MAGAZINE-PENCIL.

1,325,570.

Specification of Letters Patent.

Patented Dec. 23, 1919.

Application filed June 11, 1918. Serial No. 303,281.

To all whom it may concern:

Be it known that I, LUCIFER J. Most, a citizen of the United States, residing at New York, in the county of New York and State of New York, have invented certain new and useful Improvements in Magazine-Pencils; and I do hereby declare the following to be a full, clear, and exact description of the invention, such as will enable others skilled in the art to which it appertains to make and use the same.

This invention relates to improvements in magazine pencils and has particular reference to the general type of pencil embodied in my copending application, filed August 22, 1918, Serial No. 251,457.

The objects of the invention are to provide a pencil as described which will embody in its construction, a simple means whereby perfect alinement or register of the parts is assured when they are secured together after filling and refilling; and to provide means whereby the supply leads may be thrust simultaneously from the magazine to a point sufficiently removed from the writing end of the casing to permit the leads to be easily grasped and inserted in proper relation to the lead-projecting mechanism.

These objects are accomplished in the device disclosed in the accompanying drawings, in which similar reference numerals designate similar parts and in which

Figure 1 is a view showing the pencil in use;

Fig. 2 is a longitudinal section, slightly enlarged, through the pencil;

Fig. 3 is a detail view of a part which will hereinafter be termed the feeder;

Fig. 4 is an enlarged perspective view of some of the parts disassembled, and

Fig. 5 is a fragmentary elevation of the lower extremity of the pencil illustrating the manner of projecting the leads.

Referring, in detail, to the parts, 1 designates an outer casing. 2 is a corrugated magazine barrel which is secured concentrically within the casing and embraces a helically grooved tube or feed operating member 3. The member 3 is secured to a tube 4 forming a part of a cap 5 held upon one end of the casing 1 in such manner as to be capable of rotation thereon. A guide and lead-containing cylinder 6 is held within the tube 3 which tube extends ap-

proximately the length of the shell and is provided with a longitudinal slot 7 and a lug 8 acting to retain the cylinder 6 in its proper position.

Within the lead-containing cylinder is a 60 feeder or propelling bar 9 having a uniform thickness throughout its length and formed with a pair of offsets 10 which function in alternate grooves of the tube 3 and engage through and along the slot 7 in the lead-containing cylinder.

An inner nozzle 11, tapered at its outer extremity and formed with a threaded portion 12 at its inner proximal end, engages over and is attached to the outer end of the 70 lead-containing cylinder. This inner nozzle has soldered thereto a multi-sided extension 13, which virtually constitutes the distal end of the nozzle, and each side of which snugly engages the corresponding innermost wall of 75 each corrugation of the barrel with the angle between any two adjacent sides of the extension disposed intermediate the outermost wall of each corrugation. Provision is thus made for connecting the nozzle 11 80 with the barrel in an extremely rigid manner, and having established such rigidity, a perfect fit between the inner terminal of outer nozzle 14 and the adjacent terminal of casing 1—as at 11'. Outer nozzle 14, 85 tapered at one end and internally threaded at the other, engages the threaded portion of the inner nozzle and acts as a closing member for the magazine section.

The magazine is defined by the inner wall 90 of the shell and the outer walls of the corrugations of the barrel. In each corrugation, a lead 15 is held in reserve, while the active lead is maintained axially of the cylinder 6 and the nozzle 11. As the lead is 95 consumed, the point is fed outwardly by turning the cap 5 and the operating member 3, the grooves of which, upon engaging the offsets 10, will constrain the feeder outwardly and thus force the lead out of the 100 holder. It is obvious that an opposite turning movement of the cap will draw the feeder inwardly.

As explained at length in my copending application, when it is desired to insert a 105 new lead, the outer nozzle 14 is removed and the end of the inner nozzle is tapped against the hand or other object. In this position, as exhibited in Fig. 5, all of the leads in the magazine will partially gravitate from the 110

magazine simultaneously, being projected outwardly substantially coextensive with the end of the inner nozzle 11. Then upon slightly elevating the writing end of the pencil, any one of the leads may be withdrawn and inserted in the inner nozzle. The outer nozzle is replaced and the user proceeds to adjust the new lead for writing. The important point to bear in mind is that no matter how fragile the leads may be, they are preserved intact because the end of the nozzle receives and absorbs the impact, the nozzle strikes the object first, and the leads follow. Furthermore, the screw-threaded base 12 of the nozzle serves as an extended bearing for the leads; that is, a bearing in addition to the one afforded by the magazine. This is important, too, for when the leads have been projected as illustrated in Fig. 5, and the tips of the fingers are placed in a position to grasp one of the leads, the space is so limited that a slight flexing of the two adjacent leads is bound to ensue, and were it not for the presence of this extended bearing, the leads would be broken quite frequently.

Having thus described this invention, I claim:

1. A pencil having the combination of a casing, mechanism therein for projecting the lead, a longitudinally recessed lead supply barrel, open at the writing end, a nozzle having a screw-threaded proximal end and a multisided distal end, and a closure for the open end of the barrel engageable with said threaded end of the nozzle, said multisided end of the nozzle being rigidly secured within said barrel.
2. A pencil having the combination of a casing, lead projecting mechanism therein, a longitudinal, corrugated, tubular lead supply barrel open at the writing end, a nozzle

having a screw threaded proximal end and a multisided distal end, and a closure for the open end of the barrel engageable with 45 said threaded end of the nozzle, said multisided end of the nozzle being receivable within the end of the barrel and the angles of the said distal end of the nozzle projecting into the corrugations of the barrel. 50

3. A pencil having a casing provided with an annular reservoir adapted to hold leads, a nozzle extending from said casing having a portion thereof smaller than the interior periphery of said reservoir, means on said nozzle forming a continuation of the interior wall of said reservoir whereby leads when slid from the reservoir will be thereby spaced from the small portion of the nozzle to facilitate their being grasped by the 60 fingers, and a closure member for said reservoir.

4. The device of claim 3 in which the means comprise an enlarged shank portion 65 provided on the nozzle.

5. The device of claim 3 in which the means also coact with the closure member to keep the latter in place.

6. The device of claim 3 in which the closure member and means are threaded and 70 coact with each other to keep the closure member in place.

7. A pencil having a casing provided with an annular reservoir adapted to hold leads, a nozzle extending from said casing having 75 a portion thereof smaller than the interior periphery of said reservoir, whereby leads when slid from the reservoir will be thereby spaced from the small portion of the nozzle to facilitate their being grasped by the 80 fingers, and a closure member for said reservoir.

In testimony whereof I affix my signature.
LUCIFER J. MOST.
